UNITED STATES PATENT OFFICE.

JOSEPH KINGSLEY, OF CARROLLTON, MARYLAND.

COAL-SCUTTLE.

SPECIFICATION forming part of Letters Patent No. 314,454, dated March 24, 1885.

Application filed January 31, 1885. (No model.)

To all whom it may concern:

Be it known that I, JOSEPH KINGSLEY, a citizen of the United States, residing at Carrollton, in the county of Baltimore and State 5 of Maryland, have invented certain new and useful Improvements in Coal-Scuttles, of which the following is a specification, reference being had therein to the accompanying drawings.

My invention relates to coal-scuttles having a pivoted or adjustable hood or guard for front and spout; and in improving said article of manufacture my objects are, first, to make the article so that the hood or delivering-guard may be moved to any position to 15 regulate the size of the mouth-delivery of the hood or scuttle and be held in such position by means of pressing or clamping rivets, which permit, however, of a pivotal movement of said hood or guard; second, to effect by the 20 same means the transformation of a hooded coal hod or scuttle into the well-known coal-scuttle of commerce by bringing the pivoted hood down frontward entirely outside and below the delivery mouth or spout; third, by 25 the same means to permit the hods or scuttles to be "nested" for transportation without removing the hood from the scuttle; fourth, by an extension of the ends of the hood down upon or against the outer sides of the hood beyond 30 the points of pivot on both sides, to give to said hood an additional or supplementary elastic frictional bearing and to prevent a possible loosening or wearing of the rivet-connections.

35 I am aware of certain coal-hods which have pivoted guard-hoods; but said inventions do not aim at or effect the particular objects, as hereinbefore stated.

Referring to the accompanying drawings 40 and general description, the construction of such an article may be well understood.

In the said drawings, Figure 1 represents a coal-scuttle in perspective embracing my improvements; Fig. 2, a similar view showing the scuttle-hood as depending for its pivotal and adjusting function upon the rivets only; Fig. 3, a side elevation showing by dotted lines the various possible adjustments of the hood; Fig. 4, a diagram of the blank for the 45 hood used in Fig. 1, and Fig. 5 a diagram of that used in Fig. 2.

The hood or mouth-delivery guard A, of a form to be presently described, is pivoted at or near its ends to the coal-scuttle B, forward of the bail C, down and outside over both 55 sides of said scuttle, as at a, and in such manner and by well-understood construction of rivet-pivots as to permit of its pivotal movement when urged and of its standing in position when such urging is stopped, so that 60 the coal-delivery mouth may be regulated to any desired space, and so that the hood may be brought down over the delivery mouth or spout, for the purpose of cutting off the delivery of coal, or for converting the improved 65 scuttle into an ordinary coal-hod, or for "nesting" in transportation.

In Fig. 1 I have shown a construction of hood or guard, A, which has downward extensions e on both sides below the pivotal point 70 a, and, being constructed of sheet-iron or any of the sheet metals usually employed, will bear down upon or against the lower outer sides of the scuttle in a flexible spring-holding relation, thereby relieving in a marked degree the 75 strain expected of the rivet-pivots, adding greatly to the firm adjustment of the hood. The hoods have upon one or both their edges upset rims or spun-on wires b, to stiffen them and keep them in shape, to enable them to be 80 made of thin material, and to help their binding power, and their configuration is readily understood from the drawings.

The general object of these improvements is analogous to that of others of the class, as 85 above stated—viz., to prevent the coal from falling from the hod sidewise or over through the mouth and being scattered over the floor when the hod is handled to feed the stove; but, in addition, other results attach to the improvements, as before set forth, and also to furnish a convenient hod especially adapted to feeding what is known as "self-feeding" or "magazine" stoves, while at the same time having the function of the common hoodless 90 hod. The handle c of the hood A is placed at the side thereof, to prevent the hand from being over the fire and to bring it within easy reach. The hoods are revoluble upon the shank of rivets which have outside heads and 95 washers, d, as shown, and these pivots are placed considerably forward of the bail.

Having thus set forth my invention, I claim—

1. A coal-scuttle provided with a hood, A, adapted to be adjusted to different positions over the delivery-mouth and outside the walls thereof by means of the rivet-pivots α , substantially as described.

2. A coal-scuttle provided with a hood, A, adapted to be adjusted to different positions over the delivery-mouth and outside the walls thereof by means of the rivet-pivots α , sub-

stantially as described, the said hoods having the extensions e beyond the point of pivot, for the purpose stated.

In testimony whereof I have affixed my signature in presence of two witnesses.

JOSEPH KINGSLEY.
